UNITED STATES PATENT OFFICE.

WALTER J. BARRON, OF NEW YORK, N. Y., ASSIGNOR TO AMOS DENSMORE, OF MEADVILLE, PENNSYLVANIA, AND C. GODFREY PATTERSON, OF NEW YORK, N. Y.

TYPE-WRITING MACHINE.

SPECIFICATION forming part of Letters Patent No. 430,416, dated June 17, 1890.

Application filed January 5, 1887. Serial No. 223,471. (No model.)

To all whom it may concern:

Be it known that I, WALTER J. BARRON, a citizen of the United States, residing at New York city, in the county of New York and 5 State of New York, have invented certain new and useful Improvements in Type-Writing Machines, of which the following is a specification, reference being had therein to the accompanying drawings.

10 The object of my improvement is, first, to permit the platen to be raised independently of the paper-carriage when it is desirable to look at the writing produced; second, to have the bearings of the platen retained by 15 adjustable springs against a rigidly-supported feed-roll, and thereby permit manifolding to be as evenly printed as upon a single sheet; third, to retain the line-space lever immovable while raising the platen; fourth, to pivot 20 the front scale so that it can be pushed against the platen and take the place of two scales; fifth, to provide the type-bar with an intermediate lever to throw it up and a spring to throw it down; sixth, to provide means for 25 retaining the key-levers connected with the frame at three points and other means hereinafter described, and specifically set forth in the claims.

In said drawings, Figure 1 is a portion of a 30 type-writing machine having the parts constructed and combined in accordance with my invention. Fig. 2 is an end view of the platen, its support, the paper-feed mechanism, and its carriage. Fig. 3 is a transverse 35 vertical section of these parts, taken about the middle of their length. Fig. 4 is a vertical section of one of the type-bars, its intermediate operating-lever, and spring which throws the type-bar down. Fig. 5 is a top 40 view of the main portion of a type-writing machine, showing the improvements attached thereto. Fig. 6 is a perspective view of one 45 of the indicator-scales. Fig. 7 is a perspective view of the ribbon-feeding mechanism. Fig. 8 is a front view of the main portion of a type-writing machine having my improvements. Fig. 9 is a perspective view of one 50 of the key-levers. Fig. 10 is a front view, upon a smaller scale, of the platen and its carrying-frame turned up to show the under side thereof and its paper-guides.

In said drawings, A represents the frame, that may be of any suitable form, and A' the upper platform to which the type-bar hangers are secured. To said platform is also secured 55 the front rail A², upon which travels the wheel b of the carriage B, and the standards A³, carrying the guide-rail a, supporting the rear of said carriage.

As it has been found that sometimes the 60 letter-spacing racks become disconnected from their operating-dog when the carriage is lifted (in ordinary machines) to look at the writing, this defect has been obviated in the present case by preventing this carriage from 65 being lifted. This is accomplished by means of a strap b², secured to the front rail of the carriage and having its hooked end passing under the front guide-rail A².

To permit the writing to be seen, as shown 70 by dotted lines in Fig. 1, the platen C is carried by a rectangular frame c, having as a part of its rear portion a rod c², that is retained in U-shaped bearings c³, projecting upward from the yoke b³ of the carriage B. The 75 bearings c³ are purposely unprovided with caps, so that the frame c can be easily removed from the carriage B by slightly lifting said frame while drawing it forward; but, to prevent the accidental disconnection of the 80 parts, the frame c is retained upon its bearings by a bent spring b⁴, having its upper end resting upon the pivot-rod c² and the other end secured to the rear rail of the carriage.

To permit the platen to be lifted independently of the paper-feed mechanism or frame c to insert the paper, if desired, said platen is pivoted upon two arms C², that have their rear ends pivoted upon the rod c² of the rectangular frame above described. Under the 90 platen the feed-roll d is supported upon arms D, that are rigid in place of yielding, as heretofore, and the pressure upon the bearings of the platen, and said pressure on the platen holds the paper tightly against the feed-roll. 95 The object of this construction is to obviate a defect found in many type-writing machines when manifolding—that is, the letters are thrown out of alignment when more than one sheet of paper is used. With the present construction the relation of the type to the paper is never changed, even if twenty sheets are 100

- inserted, as the platen rises from the feed-roll instead of the feed-roll receding from the platen. The arms C^2 , carrying the platen, are retained by springs d^2 , retained adjustably secured to the frame c by means of screws d^3 passing through them about half-way of their length. One end of said springs bears upon the frame c , while the opposite end bears upon arms c^4 , projecting laterally from the frame c^2 . These springs hold the platen against the feed-roll and the paper-feed is regulated by them. If the paper happens to feed crookedly, by tightening or loosening one of the springs the difficulty is remedied.
- 15 To regulate the insertion of the paper in the machine and make corrections, a gage is used. It consists of a strip E , having numbered subdivisions. To this strip are secured jointed arms at each end, as shown in Fig. 6. One end of the arms is pivoted to a bearing e , to be secured to the front rail A^2 . This gage can be pushed against the platen and can take the place of the two scales or gages, heretofore used.
- 20 To correct an error, it is only necessary to place the carriage in a position where the pointer will indicate the first number or figure on the gage, then swing the platen up, swing the gage up against the paper, note the point on the gage where the type is to be struck, drop both gage and platen to their normal position, set pointer on carriage to the desired place on gage, and strike the key. The same object may be accomplished by
- 25 fastening the strip E to a single arm, as shown in Figs. 1 and 5. This arm has a tubular eye at its lower end and can be moved adjustably upon a rod e , that is secured at each end to the front rail A^2 .
- 30 To correct an error, it is only necessary to swing the scale against the paper, note at what point the error occurred, throw the scale back, as shown in Figs. 1 and 5, and set the pointer on the front of the carriage to the place on the scale on the front rail corresponding to the point the arrow was indicated on the scale E , and then strike the correct letter.
- In this machine the ribbon F moves with the carriage. Its spools f and f' are mounted obliquely on the ends of said carriage. They are detachable, their journals f^2 being retained by caps f^3 , secured to the carriage by thumb-screws f^4 , so that when the ribbon is all wound on the right-hand spool f' it is only necessary to reverse them and place the full spool on the left end of the carriage and the empty spool on the right end. Every time a line is to be begun the spool on the right end is revolved by the spring-pawl f^5 , pivoted to an arm F^5 , having one end pivoted to the carriage B , and the arm F^5 at the other end is supported by a spring F^6 and said arm pressed upon by a finger G' , secured to the line-space lever G , and to the latter is secured the pawl G^2 , the hooked end of which is in engagement with the ratchet-wheel of the platen; but the pawl f^5 is in position to

engage with the ratchet-wheel f^6 upon the shaft of the spool f' . By this means enough ribbon is taken up to present a fresh place for the type to strike on the next line written. The ribbon runs diagonally over the types and will not require changing or reversing often, as it is drawn forward only one-fourth of an inch each time the line is changed. Upon the journal of the spool f a coiled spring f^7 presses against a collar upon said journal to retain the ribbon under tension. The ratchet-wheel f^6 has a retaining-pawl f^8 , and under each spool there is a pendent arm f^9 , set horizontally to retain the ribbon at a proper distance under the platen. The line-space lever G is pivoted to a standard B^2 , secured upon the carriage B . It is not raised with the platen; but it carries a spring finger or pawl G^2 , the hooked end of which is in engagement with the bottom of the cog-wheel C' at the end of said platen. The line-gage lever g is pivoted to the standard B^2 , and can be set with its handle in a vertical or in a horizontal position to make a narrow or a wide space, respectively, between the lines. Each type-bar hanger h is secured to the platform A' by a screw h' , under the head of which is placed a washer that may be in the form of a continuous circle extending over all the hangers. To the inner end of the hanger is pivoted, at h^2 , one end of the type-bar H , the type-bearing end of which is automatically thrown down by a flat metal spring h^3 , secured to the top of the hanger and having its downwardly-bent end pressing upon the top of the type-bar in front of its pivot. The connecting-rod i of the key-lever I is not pivoted, as usual, to the tail end of the type-bar, but is pivoted to the tail end of an intermediate bell-crank lever i^2 , that is pivoted at i^3 to the hanger h at a point under the spring h^3 , and said lever i^2 has at its lower end an arm i^4 , that bears against the under side of the type-bar and lifts it under the impulse of the finger-key or key-lever.

It has been necessary in many type-writing machines heretofore constructed to have the type-bars work on any easy pivot, so that the bar could drop back to place after a key was struck. This pivot will wear and become so loose that the type will not always strike in the same place. By the above-described construction a close bearing can be used, as the spring h^3 will cause the type-bar to return to its normal position; but even if the pivot is loose when the type-bar is down it will be found close-fitting when said bar is up, as the spring bears against its top in close proximity to its pivot, and the bearing is nearly immovable at the moment the type strikes the paper, and it will not fail to strike it in the same spot.

To permit the key-levers I to be easily disconnected from the machine to make repairs, the reed-bar commonly used on the back part of the machine can be dispensed with. In the present instance each key-lever has inserted in or passed through its rear end a

spring-wire I², that is made to pass under a cross-bar A⁴ and over a rear bar A⁵ of the frame of the machine. The under edge of the bar A⁴ and the upper edge of the bar A⁵ are provided with serrations to retain the spring-wire I² or rear end of the key-levers in proper location. The rear portion of each key-lever has a notch I⁴ in the under side thereof to rest upon the pivotal transverse bar A⁶. The front portion of each key-lever is retained against lateral displacement by a spring-wire I³ passing vertically through said key-lever. The upper end of said wire is made to engage with perforations or serrations upon one edge of a transverse bar A⁷, secured to the frame, and the lower end of the guide-wire I³ is made to engage with similar serrations upon one edge of the transverse bar A⁸, having its ends secured, also, to the frame of the machine.

To regulate the insertion of sheets of paper under and gage them beyond the bottom of the platen, the front rod c of the platen-support is longitudinally grooved, and there are adjustably secured thereon two or more paper-guides c⁵, made of strips of sheet metal suitably curved and having upon their under face transverse gage-marks properly numbered, so that the printing made upon the first line can be made at the same distance from the top of sheets introduced consecutively under the platen or to note at what point they are taken out to make corrections. These guides c⁵ are adjustably retained upon the rod c by means of thumb-screws c⁶ passing through the eyes at their upper end and having their end impinging upon said rod.

Having now fully described my invention, I claim—

1. The combination of the paper-carriage, the frame carried thereby, flat springs adjustably secured to said frame, the platen, and its supporting-arms provided with lateral arms passing under said spring, substantially as and for the purpose described.

2. The combination of the paper-carriage, the journals of the ribbon-spools carried thereby, and a ratchet-wheel upon one of said journals with a spring-pawl carried by the paper-carriage and the line space-lever provided

with a finger adapted to bear upon the spring-pawl, substantially as and for the purpose described.

3. The combination of the front rail of the frame A' and scale thereon, the paper-carriage, the platen-supporting frame pivoted thereto, the front-supporting rail of the carriage, and the scale E, pivoted to said rail, substantially as and for the purpose described. 55

4. The combination of a type-bar hanger, the type-bar pivoted thereto, and the bell-crank lever also pivoted to the hanger and adapted to lift the type-bar, substantially as described. 60

5. The combination of a type-bar hanger, the type-bar pivoted thereto, and a sheet-metal spring secured to the hanger and bearing upon the type-bar over its pivot, substantially as and for the purpose described. 65

6. The combination of a type-bar hanger, the type-bar pivoted thereto, a spring secured to the hanger and bearing upon the type-bar, with a bell-crank lever pivoted to the hanger under said spring, substantially as described. 70

7. The combination of a type-writing-machine frame having a transverse bar A⁶ and transverse serrated bars A⁴ A⁵ with a key-lever having a notch I⁴ and a rearwardly-projecting wire I² in its rear end, substantially as described. 75

8. The combination of a type-writing-machine frame having transverse bars A⁷ A⁸, notched, as set forth, with a key-lever having a wire I³ projecting vertically therefrom 80 between the finger-keys and the pivot of said key-lever, substantially as described.

9. The combination of a paper-carriage, a platen-carrying frame pivoted thereto, springs adjustably secured upon said frame, a platen 90 yieldingly secured to said frame with a feed-roll, and rigid arms connecting said feed-roll to the platen-carrying frame, substantially as and for the purpose described.

In testimony whereof I affix my signature in presence of two witnesses.

WALTER J. BARRON.
